C. H. STENBERG,
OIL FEED FOR WICKLESS OIL BURNERS,
APPLICATION FILED JUNE 23, 1920.

Patented June 28, 1921.

2 SHEETS—SHEET 2.

Inventor:
Charles H. Stenberg.

UNITED STATES PATENT OFFICE.

CHARLES H. STENBERG, OF RADCLIFFE, IOWA.

OIL-FEED FOR WICKLESS OIL-BURNERS.

1,383,167.

Specification of Letters Patent. Patented June 28, 1921.

Application filed June 23, 1920. Serial No. 391,038.

To all whom it may concern:

Be it known that I, CHARLES H. STENBERG, a citizen of the United States, and a resident of Radcliffe, in the county of Hardin and State of Iowa, have invented a certain new and useful Oil-Feed for Wickless Oil-Burners, of which the following is a specification.

The object of my invention is to provide a reliable oil feed for a wickless oil burner of simple, durable, and inexpensive construction.

More particularly it is my object to provide such an oil feed having a wick-siphon to carry the oil from the oil reservoir and drop it into the feed pipe.

Another object is to regulate the carrying capacity of the wick-siphon automatically so as to produce a flame suitable to maintain a certain predetermined temperature surrounding the burner under varying atmospheric temperature.

With these and other objects in view, my invention consists in the construction, arrangement and combination of the various parts of the device, whereby the objects contemplated are attained, as hereinafter more fully set forth, pointed out in my claims and illustrated in the accompanying drawings, in which:

30 Figure 1 shows a plan view of the oil feed and burner.

Fig. 2 shows a cross cut view of the wick-siphon oil feed detached from the automatic regulator and burner.

35 Fig. 3 shows a cross cut view of the wickless burner.

Fig. 4 shows a horizontal cross cut view of the wick-siphon feed on a line 4—4 Fig. 2.

Fig. 5 shows a vertical cross cut sectional view of the wick-siphon feed on a line 5—5 Fig. 2.

Fig. 6 shows a vertical cross cut sectional view of the wick-siphon on a line 6—6 Fig. 2.

Fig. 7 shows an end view of that end of wick tube which extends into the oil in oil reservoir. See Figs. 6 and 2.

Fig. 8 shows a side view of same.

Fig. 9 is a sectional view of oil reservoir.

50 Fig. 10 is another sectional view of oil reservoir.

In the accompanying drawings, I have used the reference numeral 7 to indicate a casting on which is mounted the feed pipe 1 and some parts of the automatic regulator described hereinafter.

In the top end of the vertical section 1^a

is mounted a funnel shaped casting 2, having an arm 2^a. Mounted on the arm 2^a is a receptacle 3 having two compartments 3^a and 3^b. The compartment 3^a communicates 60 with the compartment 3^b near the bottom to allow oil to flow from the compartment 3^b into compartment 3^a. Mounted on compartment 3^b is an inverted jug 3^c which is provided with a cork 3^d mounted on a bail 65 3^e which extends up over the jug. The bail 3^e fits into a forked support 3^f which is secured to the receptacle 3. The receptacle 3 with the jug 3^c constitutes the oil reservoir. With the jug in place as shown in Fig. 2 70 the oil is maintained in the compartments 3^b and 3^a on a level with the opening in the neck of jug. When it is desired to replenish the oil in the jug it is removed from the receptacle 3 and set upright and filled with 75 oil. When replacing the jug, the cork is forced into the neck of the jug to prevent the oil from flowing out when the jug is inverted and replaced in the receptacle 3. When the jug is in place the bail 3^e is shoved 80 down which draws the cork from the neck of the jug and allows free flow of oil. The flow of oil is regulated by the well known principle of atmospheric pressure to maintain the oil level as described above. 85

A wick 4 is mounted in a tube 5 and extends up from the bottom of the compartment 3^a of the oil reservoir and over said compartment wall and down into the funnel 2 for a purpose described hereinafter. The wick is preferably made up into 2 or more narrow wicks, each wick held in separate compartments 5^b, clearly shown in Figs. 4, 5 and 6. The tube consists of two main parts 5 and 5^a. The wicks are placed in the part 5 and the cover 5^a is slipped over from the top. A removable bail 6 is provided to suspend the tube from the automatic regulator lever or any other suitable support. Each compartment of the tube, in that end which extends down into the oil reservoir is preferably successively shorter and is closed and perforated at 5^c and 5^d. See Figs. 6, 7 and 8.

A small extension, of that section of the wick which extends farthest down into the oil reservoir, protrudes through the end of the tube. The discharge end of the wick is preferably tapered and one section extending farther down than the others. These features are explained hereinafter.

To the end of the horizontal section of

the feed pipe 1 is connected a burner by means of threads A. A bracket 17 supports the feed pipe at this end. An asbestos ring T is set in a channel in the base of the burner which absorbs the oil and serves as a means of ignition when the oil is fed into said channel by means of the feed pipe 1 which communicates with said channel by means of the hole 18.

10 The chimney V having an inner tube U sits loosely on said burner. The inner tube is provided with a cap W.

A bracket 11 is secured to the horizontal section of the feed pipe 1. A thermostat 12 and a pivoted lever 13 which engages with the thermostat at its free end is mounted on the bracket 11.

On the upper end of casting 7 is pivotally mounted a lever 8 having a horizontal and 20 a vertical member. On the free end of the horizontal member of lever 8 is hung the which tube 5 by means of the bail 6. At a point between the base and upper end of the casting 7 is pivotally mounted a lever 9.

25 The upper end of lever 9 is pivotally connected to the free end of the vertical member of lever 8 by means of a link 10. The opposite end of the lever 9 is adjustably connected to the upper end of lever 13 by 30 means of a rod 14 having a threaded member 15 on which is fitted a threaded bur 16.

Having described the mechanical construction of the different parts, I will now explain how the different parts function individually and in combination.

35 Presuming that the oil reservoir has a full supply of oil and that all parts are in place as shown in Fig. 1. The wick-siphon has a greater carrying capacity the lower 40 the discharge end extends below the oil

level in the reservoir. The drawings show it suspended at the lowest position in which it draws its full capacity of oil from the oil reservoir and deposits it in the feed pipe

45 where it flows to the burner where it is consumed by the flame which produces the heat. As the oil is drawn from the reservoir it flows out from the jug and maintains a constant level in the compartment

50 3^a where the receiving end of the wick-siphon is submerged in the oil. It is a well known fact that a wick is not nearly so subject to clogging or variations in the flow of oil it carries as a valve commonly

55 used for such maintaining a minute and constant flow of oil for a heater of this kind. It may be said in this connection that the burner, the thermostat with the actuating connections and the jug with its attachments are of ordinary construction, hence I deem it unnecessary to give minute explanation of their functions.

If it should be desired to reduce the flame the wick-siphon is raised slightly which reduces the flow of oil, as a result of the well

known principle of a siphon whose capacity is in proportion to the length of the discharge end extending below the level of the furnace of the liquid. As an additional means of controlling the flow of oil by raising and lowering the wick-siphon I divide the wick into 2 or more parts and make the different parts of different lengths so that when the wick-siphon is raised to a certain height one of the shortest parts will 75 become free from contact with the oil and thus reduce the flow of oil. As the wick-siphon is withdrawn farther each successive part will be withdrawn from the oil and lessen the flow of oil. And vice versa when 80 an increase of the flame is wanted. As a precaution against extinguishing the flame when the automatic regulator is used to regulate the flame I provide an extension which will extend down into the oil when all other 85 parts are withdrawn and maintain a minute flow of oil. As still another additional means of controlling the flow of oil by raising and lowering the wick-siphon I taper the discharge end. The flow of oil is greater when 90 the whole width of the wick is extending below the oil level than when only the tapered end extends below. As a further precaution against extinguishing the flame when the automatic regulator is used I extend one of the wick parts with a tapered end down so that it will extend below the oil level when the actuating lever of the 95 automatic regulator on which the wick-siphon is suspended reaches the extreme 100 height of movement.

It can be seen that the wick-siphon will maintain any desired quantity flow of oil constantly without any perceptible variation.

105 It can also be seen that the thermostatic regulator will control the position of the wick-siphon so as to maintain any desired temperature surrounding the burner.

To place the wicks in the tube the cover 11^a is slipped off upward and a suitable wick is placed in each compartment. I have provided a closed end for each compartment so that the wicks can always be placed in accurate position. The closed ends are perforated at 5^a to admit the oil to the wicks. The tube is also perforated on the sides near the end 5^a to admit oil to the wick.

110 Some changes may be made in the construction and arrangement of the parts of my device without departing from the essential features and purposes thereof, and it is my intention to cover by my claims any modified forms of structure or use of mechanical equivalents, which may be reasonably included within their scope.

I claim as my invention:

1. A device of the class described in combination with an oil burner, a feed pipe, an oil reservoir, a wick-siphon designed to draw 1

oil from said reservoir and deposit said oil into said feed pipe, said wick-siphon being adjustably mounted, vertically, with relation to said reservoir, as and for the purpose stated.

2. A device of the class described in combination with an oil burner, a feed pipe, an oil reservoir, a wick-siphon designed to draw oil from said reservoir and deposit said oil into said feed pipe, said wick-siphon being adjustably mounted, vertically, with relation to said reservoir and tapered at the discharge end, as and for the purpose stated.

3. A device of the class described in combination with an oil burner, an oil reservoir, a wick-siphon mounted in a tube, said wick-siphon and tube extending from near the bottom of said reservoir and up over the sides of said reservoir and extending down into the feed pipe, said tube having two or more compartments, each compartment carrying one wick, said wick and tube compartments being removable from said oil font, with relation to each other, as and for the purpose stated.

4. A device of the class described in combination with an oil burner, an oil reservoir, a wick-siphon mounted in a tube, said wick-siphon and tube extending from near the bottom of said reservoir and up over the sides of said reservoir and extending down into the feed pipe, said tube having two or more compartments, each compartment carrying one wick, said tube compartments and wicks extending successively to lesser depths in said reservoir, as and for the purpose stated.

5. A device of the class described in combination with an oil burner, an oil reservoir, a feed pipe, a tube, a wick-siphon mounted in a tube, said wick-siphon and tube extending from near the bottom of said reservoir and up over the side of said reservoir and extending down into said feed pipe, said tube having two or more compartments, each compartment carrying one wick-siphon, said tube compartments and wick-siphons extending successively to lesser depths in said reservoir, a thermostat, an actuating device connecting said thermostat to said tube, as and for the purpose stated.

6. A device of the class described in combination, with an oil burner, a feed pipe, an oil reservoir, a tube, a wick-siphon mounted in said tube, said wick-siphon and said tube extending from near the bottom of said reservoir and up over the side of said reservoir and extending down into said feed pipe, said

tube having two or more compartments, each of said compartments carrying one said wick-siphon, said tube compartments and said wick-siphons extending successively to lesser depths in said reservoir, a small extension of said wick-siphon extending out through the end of said tube down into said reservoir, a thermostat, an actuating device connecting said thermostat to said tube, as and for the purpose stated.

7. A device of the class described in combination with an oil burner, a feed pipe, an oil reservoir, a tube, a wick-siphon mounted in said tube, said wick-siphon and said tube extending from near the bottom of said reservoir and up over the side of said reservoir and extending down into said feed pipe, said tube having two or more compartments, each of said compartments carrying one of said wick-siphons, said tube compartments and said wick-siphons extending successively to lesser depths in said reservoir, a small extension of said wick-siphon extending out through the end of said tube down into said reservoir, said wick-siphon being tapered at the discharge end and a small extension tapered and extending down from said wick-siphon at said discharge end, a thermostat, an actuating device connecting said thermostat to said tube, as and for the purpose stated.

8. A device of the class described in combination with an oil burner, a feed pipe having a funnel shaped mouth, an oil reservoir, a tube, a wick mounted in said tube, said wick and said tube extending from near the bottom of said reservoir and up over the side of said reservoir and extending down into said funnel shaped mouth of said feed pipe, said tube having two or more compartments, each of said tube compartments carrying one said wick, said tube compartments and said wicks extending successively to lesser depths in said reservoir, said tubes closed at receiving end, said tube compartments perforated at receiving end, a small extension of said wick extending out through the end of said tube down into said reservoir, said wick being tapered at the discharge end, a small extension of said wick tapered and extending down at said discharge end, said tube having a slidably removable cover, a removable bail supporting said tube, a thermostat, an actuating device connecting said thermostat to said bail, as and for the purpose stated.

Radcliffe, Iowa, June 17, 1920.

CHARLES H. STENBERG.
